COMBINED TOOL AND ACCESSORY TRAY FOR MACHINE TOOLS

Paul G. Nesteriak, Permain St.,
Shelton, Conn. 06484

Filed Oct. 23, 1967, Ser. No. 9,098

Term of patent 14 years

(Cl. D55—1)

Fig. 1

Fig. 2

Fig. 3

FIG. 2 is a back edge view thereof.

FIG. 3 is a front edge view thereof.

FIG. 4 is a bottom plan view thereof, and

FIG. 5 is a right side edge view, the left side edge view being a mirror image thereof.

I claim:

The ornamental design for a combined tool and accessory tray for machine tools, as shown and described.
